SYSTEM FOR REPRODUCTION OF SOUND
BY MEANS OF LIGHT-SENSITIVE CELLSArnold Poulsen, Hellerup, and Axel Carl Georg
Petersen, Copenhagen, DenmarkApplication October 22, 1929, Serial No. 401,581,
and in Norway October 31, 1928

2 Claims. (Cl. 250—41.5)

In the reproduction of sound recorded on a light-sensitive membrane, for instance a film, it is known to use a light-sensitive cell, for instance a selenium cell or a photo-electric cell, which is exposed to light passing through the sound record formed on the film, and is inserted in an electric circuit containing an impedance. In consequence of the current variations produced in this circuit by the varying lighting of the light-sensitive cell 5 the difference of potential which exists between the two ends of the impedance, and is impressed on to the grid of a thermionic-valve amplifier, will vary according to the lighting of the light-sensitive cell. Ordinarily the light-sensitive cell 10 is inserted directly in the grid circuit of the amplifier, and the said impedance is inserted between the two wires leading from the cell to the amplifier, and in parallel with the latter.

The insertion of a light-sensitive cell directly 20 in the grid circuit of an amplifier valve, or rather in direct conductive connection with such a grid circuit, involves the considerable drawback that the connecting wires between the cell and the amplifier must be relatively short, because otherwise the mutual capacity between these connecting 25 wires, owing to the high resistance of the light-sensitive cell as well as the considerable loading impedances occurring in the circuit, will have a considerable weakening effect on the 30 transformation of the variations of current into variations of potential in the above mentioned impedance, especially in the case of current variations with high frequency, so that a distortion 35 will be produced which cannot subsequently be compensated. A further consequence of the said considerable impedances is that very great disturbances will be induced in the said connecting wires, if they are long and come within the range 40 of external disturbing fields. When during the reproduction the sound film is moved synchronously with a picture film such fields will occur in the neighborhood of the picture mechanism owing to the driving motor or arc of the same.

It is well known that the difference between 45 the potentials induced by a disturbing conductor in two conductors parallel thereto depends essentially on the difference between the capacities to earth of the two conductors and on the magnitude of the impedance occurring between the 50 conductors, and increases with the said difference and the said impedance. Now in systems for reproduction of sound by means of light-sensitive cells the two wires leading from the cell to the amplifier device will necessarily have highly different capacities to earth, because one of the wires

will always be connected to the battery inserted in the circuit of the cell, which battery has a high capacity to earth, while the other wire will have a relatively low self-capacity to earth. As the impedance inserted between the wires in the 60 system is always relatively large, the disturbance caused in the system by stray fields may consequently become quite considerable.

In order to avoid the above mentioned drawbacks, especially when photo-electric cells are 65 used, which cells of course have a very high resistance, it has been proposed to omit the connecting wires between the cell and the amplifier entirely by building the light-sensitive cell together with the first stage or stages of the amplifier device. The light-sensitive cell must necessarily be placed in the recording apparatus proper in which the film-feeding mechanism is disposed, and this construction consequently involves the 70 drawback that vibrations produced by the film-feeding mechanism are propagated to the amplifier, for which reason the amplifier has to be suspended resiliently, and the amplifier valves have to be supported resiliently and, furthermore, that it becomes necessary to protect not only the cell 75 proper but also the amplifier against direct actuation from external stray fields.

When using selenium cells the resistance of which is not so high as the resistance of photo-electric cells it has as a rule been practicable to 80 place the first stage or stages of the amplifier device outside of the recording device proper, but the distance could not be made so large that difficulties due to induction in the amplifier in 85 consequence of the influence of the stray fields 90 could be avoided.

The present invention has for its object to remove the above mentioned drawbacks, so that long wires of any length whatever may be used between the cell and the amplifier, hereby the 95 advantage is attained that the amplifier may be placed at a point where it will not be exposed to the influence of stray fields originating from the recording apparatus or the motors, arcs etc. required for operating the same, and that the 100 induction produced in the connecting wires owing to the influence of external stray fields will be reduced to a minimum.

The desired object is attained according to the 105 invention by inserting the light-sensitive cell in the primary circuit of a transformer serving to transform downward very considerably the variations of potential produced in the circuit of the selenium cell, whereafter the thus reduced variations of potential are transmitted by way of 110

long wires to the primary winding of another transformer in which the variations of potential are transformed up to their original or possibly a higher value, and are impressed on the grid of a thermionic-valve amplifier.

The drawing shows diagrammatically two different constructions of the invention,

Fig. 1 showing the wiring diagram of a light-sensitive cell and a thermionic-valve amplifier connected thereto by way of transformers,

Figs. 2 and 3 two different constructions of corresponding wiring diagrams for a reproducing system in which a selenium cell is used as light-sensitive cell, and

Fig. 4 a reduced diagram of the wiring arrangements shown in Figs. 2 and 3.

In the construction shown in Fig. 1 c is a light-sensitive cell, for instance a photo-electric cell or any other suitable cell, inserted in a circuit containing an inductance L_1 and a battery B. One terminal of the light-sensitive cell c and one terminal of the battery B are connected to earth as shown, so that the circuit of the light-sensitive cell is closed through the earth.

The impedance L_1 forms the primary winding of a step down transformer O the secondary winding m of which is connected to the primary winding n of step-up transformer O' by means of two connecting wires a and b of any suitable length. One of these wires, viz. the wire b, belongs also to the circuit of the light-sensitive cell.

The secondary winding L_2 of the transformer O' is inserted in the grid circuit of a thermionic-valve amplifier T of known nature. k is the blocking condenser in the said grid circuit, and x is the grid leak resistance. As shown by Fig. 1 the wire b is connected to one end of each of the four transformer windings L_1 , m , n and L_2 .

The alternating current generated in the circuit of the light-sensitive cell c, when the latter is irradiated, causes corresponding variations of potential across the terminals of the primary winding L_1 which variations of potential are transformed down by the step-down transformer O, the ratio of transformation n being suitably chosen very high, and in the transformer O' the variations of potential are transformed up to their original value, the ratio of transformation being consequently

1;
n

and are then transmitted in known manner to the amplifier T. It will be seen directly that the impedance between the long wires a and b is very low in comparison with what it would be if the light-sensitive cell c were connected directly to the grid circuit in the heretofore commonly known manner, whereby for instance a large resistance is inserted between wires corresponding to wires a and b of applicants' device. In consequence of this small difference of impedance between the wires a and b in the constructions shown in Figs. 1 to 3 the difference between the potentials induced in the said two wires by disturbing external stray fields, and consequently the disturbances caused thereby will also be very small. Then the influence of the capacity between the two long wires a and b will be reduced in the ratio n^2 , and will therefore be practically annihilated when a suitable ratio of transformation n has been chosen. In order further to reduce the inductions caused by the stray fields the battery B may be placed

as shown in Fig. 1, in connection with the part of the recording system containing the amplifier T, and further the transformer O and the light-sensitive cell may be encased in a housing H of highly conductive material, for instance copper or iron, so that the eddy currents induced in the casing H will protect the cell c and the transformer O against the influence of external fields.

The casing H may consist of two shells one of which encloses the other one, and one of which is made for instance of copper, while the other one is of magnetic material for instance iron. The battery B may form part of the anode battery of the amplifier T.

Fig. 2 shows one construction of a recording system built according to the invention and using a selenium cell as the light-sensitive cell. The selenium cell S is here coupled to the amplifier valve T in a manner exactly similar to that of the cell c in Fig. 1, but an ohmic resistance r is inserted in known manner in series with the battery B and the cell S as well as the impedance L_1 the said resistance r being similarly in known manner adjusted so that in connection with the inductance of the transformer winding L_1 it will serve partly to compensate any distortions which might have been caused in the sound record by the amplitudes of sounds of low frequencies being suppressed during the recording process, cf. the specification of British Patent No. 248,148, and partly to compensate in similarly known manner, the distortions due to the selenium cell S, cf. the specification of Danish Patent No. 34,901 of August 12, 1925.

Fig. 4 shows a reduced diagram of the wiring arrangements shown in Figs. 2 and 3, the said diagram serving to illustrate graphically how the impedances of the windings L_1 and L_2 and the resistance r are included in the circuit of the selenium cell.

In the recording system shown in Fig. 2 the impedance of the winding L_1 has to be chosen so small that the product $\omega \cdot L_1$, for the highest occurring value of the frequency ω will be small relatively to the resistance of the selenium cell, while on the other hand, if for instance a photo-electric cell is used in the system shown in Fig. 1, the impedance of the winding L_1 must be chosen so high that for all frequencies the product $\omega \cdot L_1$ will be great relatively to the resistance of the photo-electric cell, or since this is practically impossible a suitable resistance must be inserted in parallel with the impedance L_1 or L_2 , all for the purpose of avoiding unintentional distortions.

Having now particularly described and ascertained the nature of our said invention and in what manner the same is to be performed, we declare that what we claim is:

1. A system for reproducing sounds from phonograms comprising a light-sensitive cell adapted to be illuminated by light passing through the phonogram, a source of current, a step-down transformer, a current circuit including in series the primary winding of the step-down transformer, the current source and the said cell; a step-up transformer, arranged together with the said current source at a relatively great distance from the light-sensitive cell and the step-down transformer, suitably long conductors by way of which the primary winding of the step-up transformer is connected across the secondary winding of the step-down transformer and a thermionic tube having a grid circuit in which the secondary winding of the step-up transformer is inserted.

2. A system for reproducing sounds from phono-
